UNITED STATES PATENT OFFICE.

JAY G. HAMILTON, OF CHICAGO, ILLINOIS.

TABLET HOLDER OR DIRECTORY.

Application filed August 7, 1922. Serial No. 530,183.

To all whom it may concern:

Be it known that I, JAY G. HAMILTON, a citizen of the United States, and resident of Chicago, in the county of Cook and State 5 of Illinois, have invented new and useful Improvements in Tablet Holders or Directories, of which the following is a description, reference being had to the accompanying drawings, which are a part of this specification.

This invention relates to a tablet holder or directory, and to a device of this character which is particularly adapted for holding a list of names of members of clubs or the 15 like.

In club houses or in office buildings or the like, there is usually provided a directory containing, for instance, the names of the members of the club or the occupants of the 20 building, and it is essential in a directory of this kind that the names may be changed with facility, as the occasion demands.

It is therefore the particular object of this invention to provide a tablet holder or directory wherein the plates or tablets, upon 25 which is delineated the desired information, may be easily positioned upon the holder, and may be removed at will.

The novel combination, construction and 30 arrangement of parts wherein the object of this invention is efficiently accomplished will be made more apparent as the description proceeds, especially when taken in connection with the accompanying drawings.

In the drawings;

Figure 1 is a front elevation of a portion of a tablet holder, constructed in accordance with the present invention; and,

Fig. 2 is a fragmentary horizontal section 40 taken on the plane indicated by the line 2-2 in Fig. 1, the view also showing by dotted lines the manner of inserting the tablets.

Referring now more particularly to the 45 drawings wherein like reference characters indicate like parts throughout, it will be seen that there is illustrated a support 10 which may be the wall of the building or any other suitable support. Secured to this 50 support is a pair of vertically extending holding members 11, suitably spaced apart to accommodate the tablets or plates 12 upon which there is adapted to be delineated such data as names or advertising matter, as 55 desired.

Connection between the tablets or plates

12 and the holding members 11 is accomplished by providing a plurality of extending grooves 13 in the holding members and forming tongues 14 on the tablets or plates 60 12. In practice these tongues 14 are adapted to be lodged in the grooves 13, as will be immediately apparent. To facilitate the insertion of the tongues 14 into these grooves and to more securely hold the tablets, the 65 opposed edges of the holding members 11 are provided with longitudinally extending grooves 15 of greater depth than the longitudinal grooves, these grooves also engaging the ends of the tablets or plates. 70

In practice the holding members 11 are secured to the wall, or other suitable support, by screws or bolts 16, and the tablets or plates 12 are flexed outwardly a sufficient distance permitted by the greater depth of 75 the longitudinal grooves to permit the insertion of the tongues 14 into the grooves 13. The plates are then released and as they straighten out, they will be securely and firmly held in position with the ends of the 80 tablets covered by the holding members, but easily removable from the holder, by inserting a knife edge beneath a medial portion of the tablet to flex it outwardly. The longitudinally extending grooves 15 facilitate 85 the insertion of the tongues 14 into the grooves 13.

In practice the wider tablets or plates will be provided with a plurality of tongues 14 and the spacing of the tongues 14 will be 90 standard, as will be the spacing of the grooves 13, so that irrespective of the width of the tablets or plates and the number of tongues carried thereby, the plates may be held in position immediately adjacent one 95 another.

From the foregoing it will be immediately apparent that there is provided a tablet holder or directory in which plates of any width may be removably held in place. 100 Furthermore, the construction is such that a simple and durable structure is provided.

While one physical embodiment of the invention is illustrated herein it is not intended that the invention be unnecessarily limited but reservation is made to make such changes as may come within the purview of the accompanying claims. 105

Having thus described the invention what is claimed is:

1. In a device of the class described, a pair of fixed holding members secured in

spaced parallel relation to a wall or the like, said holding members being formed with a plurality of equally spaced transverse grooves and opposite longitudinal grooves, a 5 plurality of flexible metal tablets having delineated thereon certain data, said metal tablets being provided with longitudinally extending tongues on their ends to enter said transverse grooves, the side edge portions 10 of the opposite ends of the tablets entering the longitudinal grooves, said metal tablets capable of being flexed to facilitate the insertion of said tongues and end side edges into said longitudinal and transverse 15 grooves.

2. A device of the class described comprising a pair of fixed spaced holding members, said holding members being provided with a plurality of equally spaced trans- 20 verse grooves, a plurality of flexible metal tablets having delineated thereon certain data, said tablets being provided with longitudinally extending tongues on their opposite ends, the opposed edges of said hold- 25 ing members being formed with longitudinally extending grooves whereby said tablets may be flexed and said tongues inserted in said transverse grooves, said longitudinal grooves engaging the side edges of the op- 30 posite ends of said tablets when said tablets are in position within the device and in a non-flexed condition.

3. In a device of the class described, a pair of spaced fixed holding members, and a plurality of flexible tablets easily remov- 35 ably interposed between said holding members by flexing said tablets, there being a longitudinally extending tongue and trans- 40 verse groove and a longitudinal groove and tablet-end-side-edge connection between the holding members and the tablets when said tablets are within the device and in a non- flexed condition.

4. A device of the class described, com- 45 prising a pair of fixed spaced holding mem- bers provided with a plurality of spaced transverse grooves and with opposite longi- 50 tudinal grooves, a plurality of flexible metal tablets having delineated thereon certain data, said metal tablets being provided with longitudinally extending tongues on their ends to enter said transverse grooves, the side edge portions of the opposite ends of the tablets entering the longitudinal grooves, said metal tablets capable of being flexed 55 to facilitate the insertion of said tongues and end side edges into said longitudinal and transverse grooves, and the longitudinal grooves being of greater depth than the transverse grooves to permit the easy inser- 60 tion and removal of said tablets.

In testimony whereof, I affix my signature.

JAY G. HAMILTON.
